UNITED STATES PATENT OFFICE

2,400,838

ENGINE BLOCK WATER HEATER

Alf P. Olson, Idaho Falls, Idaho

Application April 17, 1944, Serial No. 531,413

2 Claims. (Cl. 219—38)

This invention relates to an electric heater expressly designed and appropriately constructed for attachment to an internal combustion engine block, the same being located between the block and the radiator, this for purposes of heating the water in the cooling system in an obvious manner.

The purpose of the invention is to serve as a so-called "temporary" or "overnight heater" and it functions to sufficiently heat the water to keep it in circulation while the vehicle is in the garage or otherwise parked, whereby to render starting easier during cold weather spells.

In carrying out the principles of the invention I have adopted a simple and economical attachment having a hose and nipple on one side for connection with the radiator, and having nipples on the other side to accommodate complementary hoses connected with the usual expansion plug-holes in the cylinder block.

More specifically the attachment comprises a nipple-equipped hose-accommodating cylindrical unit constructed at one end for detachable connection of the electrically heated core element, the latter being such that it can be used in association with either A. C. or D. C. current and the construction being such as to keep the water at approximately 100 degrees F. when the outside temperature is at freezing or below, thus insuring easy starting of the engine.

Other features and advantages will become more readily apparent from the following description and the accompanying illustrative drawings.

In the drawings, wherein like numerals are employed to designate like parts throughout the same—

Figure 1 is a side elevational view of a conventional internal combustion engine with radiator associated therewith and showing the improved heater attachment and the manner in which it is constructed and applied.

Figure 2 is an enlarged view, partly in section and partly in elevation of the essential parts of the invention.

Figure 3 is a cross-section on the line 3—3 of Figure 2 looking in the direction of the arrows.

In Figure 1 the motor block or engine, as a unit, is indicated at A and the radiator at B, these being conventional parts. As brought out better in Figure 2, the attachment comprises a substantially cylindrical casing of appropriate material and dimensions indicated by the numeral 4, this being closed at the left-hand end and provided with an internally screw-threaded

accommodation neck 5 at the right-hand end. The electric heating element or core 6 fits into the cylinder in spaced relation and is provided with a screw-threaded connection 7 threaded into the neck, this connection being on a nut faced head 8. A gasket 9 is interposed between the parts 5 and 8 to provide the desired fluid-tight joint. The electric conductor cord 10 is provided with a plug 11 to accommodate a pronged plug 12 on an extension cord 13, whereby to provide convenient means for supplying current to the heating element 11. It is understood that the particular wiring and method of connecting the wires is not important and is, therefore, not detailed.

15 On the lower side the casing 4 is provided with a nipple 14 to which an adjacent end of the radiator hose 15 is connected. The opposite end of the hose is secured to the bottom of the radiator as shown in Figure 1. Similar nipples 16

20 and 17 are arranged on the opposite side, these to accommodate the shorter hoses 18, which latter hoses are suitably fastened to the nipples and also secured to fittings 19 mounted in the customary expansion plug-holes in one side of 25 the water jacket of the cylinder block, this as brought out in Figure 1.

With the current "on" the core element 6 serves to circulate the water through the hoses, radiator and cylinder block in an obvious manner, thus keeping it at a temperature sufficient to avoid freezing and promote pump starting, this in an evident manner.

It is thought that persons skilled in the art to which the invention relates will be able to 35 obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

45 1. An electric circulatory water heater attachment for conventional internal combustion engine blocks comprising a cylinder, the latter being closed at one end and having a reduced internally screw-threaded neck at its opposite end, 50 said cylinder being provided on the central portion of its normal bottom with a nipple to accommodate a hose for connection with the associated radiator, and being further provided at diametrically opposite points with outstanding 55 longitudinally spaced additional nipples, these to

accommodate hose line connections for connection with the customary expansion plug holes in the cylinder block, a screw-plug having an electric heating core element, said core element being located in spaced concentric relation on the interior of said cylinder, said plug being threaded in said neck and being provided with a wrench grip and an electric current-conducting cable.

2. An electric circulatory water heater attachment for conventional internal combustion engine blocks comprising a cylinder, the latter being closed at one end and having a neck at its opposite end, said cylinder being provided on the central portion of its normal bottom with a hose

for connection with the associated radiator, and being further provided at diametrically opposite points with outstanding longitudinally spaced additional nipples, these to accommodate hose line connections for connection with the customary expansion plug holes in the cylinder block, a plug having an electric heating core element, said core element being located in spaced concentric relation on the interior of said cylinder, said plug being mounted in said neck and being provided with a tool grip and an electric current-conducting cable.
